(57) **CLAIM**

The ornamental design for a control handle for tap as shown and described.

DESCRIPTION

1. Control handle for tap

1.1 : Perspective

1.2 : Front

1.3 : Left

1.4 : Right

1.5 : Top

1.6 : Bottom

The evenly spaced broken lines illustrate environmental subject matter and form no part of the claimed design. The long-short-short dashed broken lines in FIG. 1.6 illustrate portions of the control handle for tap that form no part of the claimed design.
